CLAIM

The ornamental design for a garment with pockets, as shown and described.

DESCRIPTION

FIG. 1 is a perspective front view of a garment with pockets in environmental conditions showing my new design;
FIG. 2 is a right side view thereof;
FIG. 3 is a left side view thereof;
FIG. 4 is a top plan view thereof;
FIG. 5 is a bottom plan view thereof;
FIG. 6 is a cross-sectional view thereof, taken along line 6-6 in FIG. 4; and,
FIG. 7 is an enlarged view thereof, taken from FIG. 6.
The broken lines in the drawings depict portions of the garment with pockets that form no part of the claimed design.
